His Attorney

UNITED STATES PATENT OFFICE

HANS NEUBERT, OF ANNABERG, GERMANY, ASSIGNOR TO GENERAL ELECTRIC COMPANY, A CORPORATION OF NEW YORK

ELECTRICAL CONNECTER

Application filed July 15, 1927, Serial No. 206,039, and in Germany November 26, 1926.

My invention relates to electric connectors, more specifically to connectors of the detachable type such as used on electric cooking and heating appliances, and has for its object the provision of a simple, reliable and efficient means of this character which operates at a reduced temperature.

Devices for connecting up electric heating and cooking utensils, for instance, plug contacts, often attain very high temperature when in operation. This heat is transmitted from the contact device to the conductors leading thereto and endangers the insulation of the latter.

According to the invention the temperature of the contact device is reduced in that the temperature drop in the contact device itself is increased. This object is attained by making the contact device of insulating material which is a poor conductor of heat, such, for instance, as porcelain, which contains the current feed conductor in its interior. At its end the feed conductor is connected to a small contact cap which only partially encloses the pin of insulating material. The conduction of heat can be further reduced by making the feed conductor of band form and by reducing the contacting surface between the contact device and the wall of the utensil.

For a more complete understanding of my invention reference should be had to the accompanying drawing, the single figure of which is a sectional view of a connector for cooking utensil embodying this invention.

Referring to the drawing, the invention is shown in one form as a pin or plug contact over which a suitable plug socket connected to a feed conductor may be placed. The pin, or plug, 10 consists of porcelain or other suitable material, which is a poor conductor of heat. The feed conductor 11, which may consist of a circular wire or a wire of band form, extends through a central aperture in the pin and terminates in a contact cap 12 which only partially surrounds the pin. It will be understood that the conductor 11 is connected to one terminal of an electric heating resistance unit, not shown.

In order to still further reduce the transmission of heat from the utensil wall 13, the

pin 10 has an enlarged base and is provided at the surface on which it rests with projections 14 which contact with the utensil wall at points only. The attachment of the pin 10 to the wall 13 is effected by means of a nut 55 15 which presses the porcelain ring 16 against the asbestos disk 17. The porcelain ring 16 is also provided with bearing projections 18 so that it will not press with the whole of its adjacent face against the asbestos disk 17. As shown, the projections 14 fit in openings 19 in the utensil wall.

The invention is, of course, not restricted to pin or plug devices but may also be employed for connections with screw contacts.

What I claim as new and desire to secure by Letters Patent is:

1. A connector for electric heaters comprising a pin made of electrically insulating material, projections on said pin forming supports of poor heat conductivity therefor, a conductor extending through said pin, and a cap on said pin connected to said conductor.

2. A connector for electric heaters comprising a pin made of electrically insulating material, projections on one end of said pin forming supports of poor heat conductivity therefor, a conductor extending through said pin, a cap on said pin connected to said conductor, and a clamping member for said pin 75 80 provided with bearing projections.

In witness whereof, I have hereunto set my hand this 11 day of June, 1927.

HANS NEUBERT.
